Inventor:

W. M. Mayall

United States Patent Office.

WILLIAM M. MAYALL, OF GRAY, MAINE, ASSIGNOR TO HIMSELF AND
JOHN C. MAYALL, OF BOSTON, MASSACHUSETTS.

Letters Patent No. 96,938, dated November 16, 1869.

IMPROVEMENT IN CORN-SHELLERS.

The Schedule referred to in these Letters Patent and making part of the same.

To all persons to whom these presents shall come:

Be it known that I, WILLIAM M. MAYALL, of Gray, in the county of Cumberland, and State of Maine, have invented certain new and useful "Improvements in Corn-Shellers;" and that the following is a full and complete description of the same, reference being had to the accompanying plate of drawings, forming a part thereof.

My invention consists—

First, in arranging, with the shelling-jaws, a series of wheels, whereby the operation of shelling is increased, the friction decreased, and the feeding improved.

Secondly, in a novel construction of clamp, by means of which the sheller can be secured to the edge of a table, or other horizontal plane, or to the side of a tub, or other vertical plane, as may be desired.

Thirdly, in the combination and arrangement of various parts, as will be hereafter set forth.

In the accompanying plate of drawings, my improvements in corn-shellers are illustrated—

Figure 1 being an elevation from one side;

Figures 2 and 3, end elevations;

Figure 4, a longitudinal vertical section, taken in the plane of the line *x* *x*, fig. 3;

Figure 5, detail sectional view, in the plane of the line *y* *y*, fig. 1; and

Figure 6, detail sectional view in the plane of the line *z* *z*, fig. 1.

A, in the drawings, represents an upright or post, in the upper end of which is hung, by its centre shaft, *B*, a large bevel-gear wheel, *C*.

D, handle secured to gear-wheel *C*, for convenience in turning it.

E, bevel-gear wheel, hung in a two-part circular strap, *F*.

One part, *G*, of this strap *F*, is of one and the same piece of metal as the upright *A*, and the other, *H*, detachable, and provided with screw-holes, for bolting it to the part *G*.

By means of the said strap *F*, the said bevel-gear wheel *E* is held in position, and as engaged with the gear-wheel *C*.

The gear-wheel *E* is left open through its centre, *K*.

L, a circular flange or rim, extending beyond the face *M*, to the gear *E*.

N, shelling-blades, arranged within the flange *L*, upon parallel guide-rods, *O*, fixed in said flange, and extended across from one side to the other of the same.

The shelling-faces *P* are concave from end to end, and are arranged opposite to each other, being acted upon by spiral springs *Q*, placed over the guide-rods *O*, between the jaws *N* and the flange *L*.

R, wheels, arranged in the shelling-jaws, and, by their edges, projecting into the space between the jaws.

By means of these wheels the action of the shelling-jaws is facilitated, their friction decreased, and their tendency to draw or feed through the ear of corn much increased and improved, and with less expenditure of power.

S, a vertical frame, secured by strap *T*, with screws, *U*, to upright or post *A*.

V, two rolls, concave in shape, from end to end.

These rolls are hung, one above the other, in the frame *S*, between its side upright, *W*, in which they have bearings, and are arranged, by means of sliding boxes *X*, and spiral springs *Y*, to be susceptible of opening from or closing upon each other.

These rollers, when in position upon the upright *A*, extend across the open gear-wheel *E*, and are located upon the opposite end of such gear to that having the shelling-blades, as plainly shown in the drawings.

Z, pinion-wheel, on main gear-wheel shaft *B*, and

*A*², pinion-wheel, gearing into said pinion *Z*.

*C*², shaft of pinion-wheel *A*², carrying another pinion-wheel, *D*², arranged to engage with a pinion-wheel, *E*², on the shaft, to one of the rolls *V*.

By means of this gearing, such roll, with its mate, is turned.

The lower end, *F*², of post *A*, is turned off, to adapt it to receive a clamp, for clamping the machine to a suitable place.

The clamp *A*⁴, under the present invention, is made with a slit or opening, *G*², by which it can be set over and upon the edge of a table or tub, where, by means of a thumb-screw, *H*², it can be secured.

*I*² and *J*², two holes in clamp *A*⁴, in planes at right angles, or nearly so, to each other.

By these holes the clamp can be set on the turned-off end of the post *A*, according as it is desired to bring the slit *G*², of the clamp, into a horizontal or vertical position, for fixing the machine to a table or tub, &c.

*L*², set-screw, provided for the receiving-holes of the clamp *A*⁴, into which the post *A* is set.

In shelling corn by my improved machine, first place the ear, by one end, in the jaws *N*, when, turning the gear-wheel *C*, such jaws are carried around the ear, removing the kernels therefrom, and passing the ear through the hollow gear-wheel *E* to and between the rolls *V*, by means of which it is not only held from turning, thus leaving the hand of the person free, but to a greater or lesser extent drawn through the jaws.

The rim or flange *L* acts as a shield to the shelling.

jaws, preventing the kernels from being spread or thrown out and scattered about, as they are removed by the shelling-jaws.

Having thus described my improvements, I shall state my claims, as follows:

1. The wheels R, to the shelling-jaws, for the purpose specified.
2. The clamp A⁴, constructed with slit G², and holes I² and J², substantially as described, for the purpose set forth.

3. The combination and arrangement of the flange L, shellers N, rollers R, guide-rods O, springs Q, rolls V, springs Y, and gear-wheels C E, substantially as herein represented and described.

WM. M. MAYALL.
